UNITED STATES PATENT OFFICE.

HENRY SUMNER GARDNER, OF BINGHAMTON, NEW YORK.

COUNTER-FLASHING ATTACHMENT.

1,210,060.

Specification of Letters Patent. Patented Dec. 26, 1916.

Application filed October 6, 1916. Serial No. 124,127.

To all whom it may concern:

Be it known that I, HENRY SUMNER GARDNER, a citizen of the United States, residing at Binghamton, in the county of 5 Broome and State of New York, have invented a new and useful Counter-Flashing Attachment, of which the following is a specification.

The device forming the subject matter of 10 this application is adapted to be employed for securing a flashing to a parapet, and the present invention aims to provide novel means whereby this operation may be carried out with a minimum expenditure of 15 effort and material, the means for receiving the flashing being assembled with a part of the molding structure whereby the parapet is fashioned.

Another object of the invention is to provide 20 novel means whereby a leakage of water into the channel which receives the counter-flashing will be prevented.

It is within the province of the disclosure to improve generally and to enhance the 25 utility of devices of that type to which the present invention appertains.

With the above and other objects in view which will appear as the description proceeds, the invention resides in the combination 30 and arrangement of parts and in the details of construction hereinafter described and claimed, it being understood that changes in the precise embodiment of the invention herein disclosed can be made within 35 in the scope of what is claimed, without departing from the spirit of the invention.

In the accompanying drawings:—Figure 1 is a sectional perspective illustrating the structure as it will appear after the parapet 40 has been formed, and before the flashing has been applied; Fig. 2 is a vertical section showing parts as the same will appear after the molding structure for the parapet has been removed; Fig. 3 is a vertical sectional view wherein the means for receiving the 45 flashing is shown connected to one of the elements of the molding structure; Fig. 4 is a transverse sectional view showing the device in its completed condition.

In the accompanying drawing, the 50 numeral 1 indicates the wall of a building, ordinarily made of concrete, the numeral 2 designating a parapet constituting a part of the wall. Surmounting the parapet is a coping 3. The roof timbers are shown at 4, and the roof appears at 5. The wall 1 and

the parapet 2 are fashioned to one side of an outer form 6, the numeral 7 indicating an inner form which, coöperating with the outer form, defines the parapet 2.

In carrying out the present invention there is provided a metal channel 8 of any desired length, the walls 9 of which converge as they extend outwardly, the walls 9 being provided with oppositely projecting flanges 10 and 10^a, the flange 10 extending upwardly, and the flange 10^a extending downwardly. The flanges 10 and 10^a are attached, respectively, by securing elements 11 and 11^a to the inner face of the form 7. 70 The securing elements 11 preferably are tacks or short nails.

In practical operation, the forms 7 and 6 are set up as shown in Fig. 1, the channel 8 being attached by means of the securing elements 11 and 11^a to the inner face of the form 7, as shown in Fig. 3. The concrete is then introduced between the forms, and the parapet 2 is built up. The form 7 then may be removed, the securing elements 11 and 11^a 80 being drawn readily out of the form. The channel 8 thus is inserted into the parapet 2, as clearly shown in Fig. 2, the flanges 10 and 10^a of the channel 8 overlapping the outer face of the parapet.

The numeral 12 indicates a counter-flashing strip of any desired length, provided along its upper edge with a slanting extension 14 adapted to coact with the lower wall of the channel 8, the extension 14 terminating in an upstanding lip 15 which, preferably, abuts against the base or inner wall of the channel 8, in a manner which will be understood clearly from Fig. 2. The flashing 12 thus is assembled with the channel 8. 95 The upper flange 10 may then be bent downwardly, to overlap the counter-flashing 12, as indicated in Fig. 4. This construction prevents water flowing down the parapet 2 from entering the channel 3. It is to be observed that when the flange 10 is bent downwardly, the securing element 11 may be removed. The securing element 11^a, however, remains in the flange 10^a and may be pushed through the flashing 12. The securing element 11^a, further, may be passed through the hole in the flange 10, formerly occupied by the securing element 11, and then the securing element 11^a may be clenched down on the outer face of the flange 10^a, as shown at 16 after the flange 10 has been bent down as indicated in Fig. 4.

One of the advantages of the structure shown in Fig. 4 is that it is unnecessary, ordinarily, to fill the channel 8 with cement, since the flange 10, when the same is bent 5 downwardly as shown serves at once as a water shed for the channel 8, and as a means for holding the flashing 12 in place.

The device forming the subject matter of this application has been shown in connection with a concrete parapet 2. It will be understood that the device is equally applicable to a brick parapet, under which circumstances, the channel 8 will be mounted in the mortar between the bricks. Such a construction will be understood readily by a skilled mechanic, and a showing in the drawings of the structure last above described is considered unnecessary.

Having thus described the invention, what 20 is claimed is:—

The combination with a wall, of a channel embedded therein and having upstanding

and depending flanges; securing elements connected with the flanges and constituting means for attaching the channel to a mold; a flashing including an extension prolonged into the channel, the upstanding flange being bendable to constitute a closure for the channel and to overlie the outer face of the flashing; the securing element of the upstanding flange being removable to form a hole, and the securing element of the lower flange being extended through the flashing and through the hole, and being clenched on the outer face of the upstanding flange 30 after the said flange has been bent downwardly.

In testimony that I claim the foregoing as my own, I have hereto affixed my signature in the presence of two witnesses.

HENRY SUMNER GARDNER.
